UNITED STATES PATENT OFFICE

EDWARD S. SAVAGE, OF ROCHESTER, NEW YORK

SELF-PROPELLED FIGURE TOY

Application filed April 30, 1930. Serial No. 448,700.

The present invention relates to figure toys and more particularly to the type in which a body is supported by one or more pairs of legs or supports pivoted to the body and each 5 having its lower end or foot portion provided with a rolling supporting surface, the rolling supporting surfaces on the members of a pair of supports having their elements arranged at oblique but opposite angles to a median 10 plane through the body so that the body may roll on one support and then tilt sidewise and roll on the other support and vice versa. An object of this invention is to make it possible to obtain a self propelled toy which will happen 15 hazardly reverse its direction of motion so as to simulate different actions such as walking forward and backward, hesitation, whirling or dancing. While is not claimed to produce all of these movements in one and the 20 same toy, the invention makes it possible to construct individual toys that will simulate one or more of these motions. Another object of the invention is to produce a self propelled walking toy that may be caused to walk in 25 either forward or backward direction without the use of any special reversing mechanism. To these and other ends, the invention 30 consists of certain parts and combinations of parts, all of which will be hereinafter described: the novel features being pointed out in the appended claims.

In the drawings:

Fig. 1 is a face view of a two legged figure toy with parts in section;

Fig. 2 is a side view of the same figure with parts in section;

Figs. 3, 4 and 5 are respectively an inner side view, a top view and an outer side view of one of the feet of the figure shown in Figs. 1 and 2;

Fig. 6 is a front view of a four legged figure toy embodying the present invention;

Fig. 7 is a side view of the toy shown in Fig. 6 with parts in section;

Fig. 8 is a side view of another embodiment of the toy;

Fig. 9 is a diagrammatic view of the bottom surface of one of the feet of the toy shown in Fig. 7;

Fig. 10 is a plan view of such foot; and

Fig. 11 is a side view of such foot.

Toys of the type mentioned have heretofore merely moved forwardly by means of a pull cord or by rolling down an inclined surface, whereas, in this invention, the toy is equipped with a motor which moves one support of a pair forwardly as the other support of the pair is moved rearwardly and vice versa. The angularity of the elements of the rolling surfaces of the supports in relation to a median 55 plane through the toy is such that the toy while at rest will stand on either supporting surface but in either position it is in a state of unstable equilibrium in that it is easily tilted from one side to the other. When in motion the toy tilts from side to side, the tilting usually occurring at the end of each swing of the supports, but if, due to irregularities of the supporting surface or to momentum of the swinging support, this tilting occurs 60 before the completion of the swing of the support a reversal will occur and the direction of the movement of the toy will be changed. Means may be employed which will give to the toy a preferred direction of movement, but 65 even under this condition slight irregularities of the surface upon which the toy travels often effect a reversal of the direction of movement. This action takes place whether the toy has one pair of supports or more. 70 When a single pair of supports forms the sole supporting means of the toy this reversing action produces rotary movement causing the toy to revolve about upright axes to change 75 its frontal position, due to the fact that the movement and resultant momentum imparted to one support through the motor while that support is off the supporting surface tends to produce a turning or sidewise action of the body on the other support. This form of the 80 invention makes the toy simulate a dancing action.

In the embodiment shown in Figs. 1 to 5 inclusive, a toy is illustrated which simulates dancing. The hollow body 1 is formed, in 85 this instance, of light material such as celluloid and has in this instance, a head 2 and arms 3 formed of the same material. This body is supported by bracket arms 4 from the frame 5 of a spring motor within the body. 90

This frame carries, adjacent the lower part of the body 1, a fixed shaft 6 on which the two legs 7 are mounted to swing side by side, being spaced from each other by a sleeve 8. 5 The legs are also formed of light sheet material such as tin and the feet 9 are formed of any plastic material in which the legs are embedded and which also has embedded therein weights 10. 10 The feet have rolling contact surfaces 11 which, in this instance, are cylindrical surfaces 12 throughout the length of the foot except at the toes 13 which may be spirally formed. In outline the feet are rounded at 15 both toe and heel. The elements of the cylindrical contact surface of each foot form an oblique angle to the median line through the body or incline upwardly from the inner side of the foot, as by this arrangement when the 20 leg is rolling on one foot surface the other foot surface will be out of contact with the supporting surface on which the toy is moving so that the latter foot may be shifted forwardly relatively to the body. As the 25 engaging portion of each foot approaches the toe the body shifts laterally and inwardly onto the heel portion of the other foot due to lack of support because of the round toe and assisted by the spiral toe portion 13 and the 30 body proceeds to roll forwardly on the other foot and the first foot shifts forwardly during this rolling action on the second foot. The forward direction of motion is not however positive and the toy will frequently 35 hesitate and reverse its direction of motion. The shifting of the body from one foot to the other is effected primarily by the curves on the toes or the heels of the feet, depending upon the direction the toy is moving. As 40 a foot moves forwardly or backwardly on a surface, the point or line of contact with the supporting surface finally reaches the curved end of the foot, and, as the center of gravity of the toy is near the inner side of the sup- 45 porting foot, the toy loses its balance and tips inwardly bringing the other foot in contact with the supporting surface and raising the first foot out of contact with the supporting surface. The effect of the spirals at the 50 toes 13 is to give the toy a greater tendency to move forward but does not prevent its moving backward at times.

The motor for operating the legs of the body, in this instance, is in the form of a 55 volute or clock spring 14 connected at one end to a winding shaft 15 exposed through an opening in the body. The other end of the spring connects with a gear 16 which connects by gearing 17 with a crank shaft 18 60 having two cranks 19 connected by links or pitmen 20 with eccentric portions 21 on the legs 7.

Associated with the motor is a governor comprising, in this instance, an escapement 65 wheel 22 on the crank shaft 18 engaging

prongs 18^b on the oscillator shaft 23 which carries one or more, (in this case two) arms 24 with weights 25 which are rigidly but adjustably secured. By associating with the motor, especially a high power motor, a governor which will reduce the speed of the leg action, this whirling or dancing movement may be eliminated and a more steady walking action obtained but reversing taking place under certain conditions. The governor is made adjustable so that it may easily be set to produce either the slower action or the quicker more irregular dancing action. The weighted feet and light body have the effect of holding the body upright on its feet. 70

In the embodiment shown in Figs. 6 and 7 the invention is embodied in a four legged walking toy simulating a mule. In this instance, 1^a indicates a hollow body having two shafts 6^a on each of which two legs 7^a swing. 75 Above these shafts the legs have pins 21^a projecting laterally through curved slots in the body. 80

Within the body is the spring motor 14^a which has its crank shaft 18^a having cranks 19^a at opposite ends at 180° from each other, each crank having two links 20^a connected thereto and extending to the pins 21^a of a front and a back leg on the same side of the body. To the crank shaft is attached an escapement wheel 22^a which engages the prongs on a shaft 23^a which carries the governor arms 24^a on which the adjustable weights 25^a are arranged. The feet 9^a, in this instance, are not weighted but the under surfaces are 90 formed similarly to the under surfaces of the other embodiments. As four feet are employed, instead of two, as in the first embodiment, the weights in the feet are not needed although the toy should not be top heavy. It 95 has been found that, with a four legged toy operating on this principle, if the toy meets with resistance or irregularities of the supporting surface, then the rhythm of its side- 100 wise swinging or oscillating motion may be disturbed and it will tip from one pair of feet to the other pair before its normal travel on the first pair has been completed. When this occurs the toy stops and starts again in the opposite direction and continues to move in 105 this backward direction until its rhythmic swing is again disturbed and it again reverses its direction of travel and moves forwardly. 110

It may repeat this performance a number of times until the spring is unwound. This, especially when the toy is embodied in a mule or donkey, gives an appearance of stubbornness, a characteristic of the mule or donkey. 115

In the embodiment shown in Fig. 8 the parts being substantially like those shown in Figs. 1 and 2 are numbered the same except that the feet 9^b are not necessarily weighted. A support 26 is extended rearwardly and 120 downwardly from the body and has a roller 27 at its lower end for travelling on the surface 125 130

on which the toy is moving serving with either foot to balance the toy and prevent its turning or changing its frontal position while walking. This guide roller or its equivalent 5 may be placed in any effective position with reference to the figure to prevent this turning action.

What I claim as my invention and desire to secure by Letters Patent is:

10 1. A self propelled and reversing toy comprising a body, two supports pivoted to the body side by side and having their lower ends provided with curved rolling supporting surfaces inclined upwardly and outwardly 15 from a median plane through the body, means for effecting the shifting of the toy alternately on the two supports as the supports successively approach the ends of their rolling movements, a motor on the toy, and 20 connecting means between the motor and the two supports positively moving the supports in opposite directions relatively to the body while the toy is rolling on each surface.

25 2. A self propelled and reversing toy comprising a body, two supports pivoted to the body and having curved rolling supporting surfaces inclined upwardly and outwardly from a median plane through the body, a motor on the toy, and connecting means between the motor and the supports swinging them positively in opposite directions relatively to the body while the toy is rolling on each surface.

30 3. A self propelled and reversing toy comprising a body, two supports pivoted to the body side by side and having their lower ends provided with curved rolling supporting surfaces inclined upwardly and outwardly from a median plane through the body, a 35 motor on the toy, connecting means between the motor and the two supports swinging the supports positively in opposite directions relatively to the body while the toy is rolling on each surface, and a governor for the motor 40 retarding the action of the latter to vary the type of walking action of the toy.

45 4. A self propelled reversing toy comprising a body, two supports pivoted to the body and having curved rolling surfaces inclined 50 upwardly and outwardly from a median plane through the body, the angle of inclination of the elements of the surfaces near their forward ends being greater than the angles of the other elements so as to give the toy a 55 greater tendency to walk in a forward direction, a motor carried by the toy, and connecting means between the motor and the supports swinging them positively in opposite directions relatively to the body while the 60 toy is rolling on each surface.

55 5. A self propelled reversing toy comprising a body, two supports pivoted to the body and having curved rolling supporting surfaces inclined upwardly and outwardly from 65 a median plane through the body, a motor on

the toy, means for effecting the shifting of the body sidewise as it approaches either end of each rolling surface to cause the body to roll on the other rolling surface, and connecting means between the motor and the two supports moving that support on which the body is rolling to swing in one direction, and the other support which is free from the surface on which the body is rolling, in the other direction.

6. A self propelled dancing toy comprising a body, two supports pivoted to the body side by side and having feet at their lower ends, the under surface of each foot being curved from front to rear, providing curved rolling surfaces, said supports forming the sole supporting means of the body, a motor on the toy, and connecting means between the motor and the two supports positively moving the supports in opposite directions relatively to the body while the toy is rolling on each surface and imparting to each support, while it is out of engagement with said surface, a momentum which changes the frontal position of the toy on the other support.

7. A self propelled dancing toy comprising a body, two supports forming the sole supporting means of the body, pivoted to the body and having feet at their lower ends, the under surface of each foot being curved from front to rear, providing curved rolling surfaces on which the body is alternately supported and rocks alternately, and motor mechanism carried by said body and connected to the supports to operate them alternately in opposite directions to change the frontal position of the toy while it is supported on each rolling surface.
